UNITED STATES PATENT OFFICE.

NORA PARKER, OF OXFORD, MICHIGAN.

DESIGN FOR A CORSET STAY MEMBER.

SPECIFICATION forming part of Design No. 35,123, dated September 17, 1901.

Application filed July 10, 1901. Serial No. 67,797. Term of patent 7 years.

To all whom it may concern:

Be it known that I, NORA PARKER, a citizen of the United States, residing at Oxford, in the county of Oakland and State of Michigan, have invented and produced a new and original Design for a Corset Stay Member; and I do hereby declare the following to be a full, clear, and exact description of the same, reference being had to the accompanying drawings, forming a part thereof.

Figure 1 represents a perspective view, and Fig. 2 a cross-section on the line $x x$ of Fig. 1.

The leading or material feature of my design is shown in the drawings, in which A designates the member, provided at one end with the portions a , which project inward to-

ward each other from opposite sides and extending from one end for a portion of the length of the member, the said portions a being in a different plane than the body portion.

Having thus described my invention, what I claim as new, and desire to secure by Letters Patent, is—

The design for a corset stay member substantially as shown and described.

In testimony whereof I affix my signature in presence of two witnesses.

NORA PARKER.

Witnesses:

FRANK E. JENKINS,
CARRIE HAINES.
